COKING PROCESS

Ernest Utterback, Upper Darby, Pa., assignor to
 Socony-Vacuum Oil Company, Incorporated,
 New York, N. Y., a corporation of New York

Application July 25, 1941, Serial No. 403,989

5 Claims. (Cl. 202—36)

This invention is directed to spray coking processes for the reduction of heavy oils to coke and has particularly to do with the removal of particle form coke from such systems.

Various processes have been developed in which a relatively dry particle-form or granular coke is produced by some modification of the general operation of spray coking. One of the major difficulties of such processes is the method of removal of coke particles from the chamber wherein they are formed. The usual devices partake of the nature of paired valves, one of which is open while the other is closed; sliding plate valves; star wheels; and similar devices. This is because an entry of air into the coking chamber, or, more usually, the exit of vapors therefrom, must be avoided. None of these devices has proven particularly satisfactory.

This invention has for its object the provision of a method whereby the coke may be removed by means such as are usually appropriate for handling fluids, and whereby the coking chamber may be continuously isolated from the atmosphere while coke is being continuously removed.

In order to understand this invention, reference is made to the accompanying drawing, the single figure of which shows, in diagram form, a set-up of apparatus whereby the process of my invention may be practiced.

In this drawing 1 is a chamber in which by some process of spray coking, a granular or particle form of coke, more or less dry, is being produced. This coke falls to the cone-like bottom of 1, and passes through duct 2 into vessel 3. In vessel 3 there is maintained a pool of refractory oil, of the nature of gas oil, for example, cracked recycle stock, into which the coke falls and within which it is suspended. The mixture of oil and coke is withdrawn through pipe 5 by pump 6. Pump 6 may be any form of pump capable of handling a mixture of liquid and some solids, such as, for example, the "Hydroseal" pump developed and sold by the Worthington Pump and Machinery Corporation of New York. The discharge from pump 6 passes through pipe 7 to either of separators 8 and 9, each of which is provided with a screen 10, and the coke remains thereon, the oil passing away through pipe 11. The oil in pipe 11 is cooled by passage through heat exchanger 12 and delivered into pipe 13. As a usual thing this oil is returned from pipe 13 through valve 14 to vessel 3, valve 14 being operated in response to liquid level control 15 to maintain a predetermined level of oil in vessel 3. If more oil is delivered to pipe 13

than the momentary demand in vessel 3 calls for, the surplus is delivered to tank 16 through valve 17 which is arranged to be responsive to a predetermined pressure in pipe 13. Additional 5 and auxiliary control over the amount of oil withdrawn from vessel 3 (and consequently of the level maintained in 3), is provided by pipe 18, pump 19 and valve 20, valve 20 being so interconnected with liquid level control 15 and valve 14 that when valve 14, wide open, fails to maintain level, valve 20 opens to provide additional oil from pipe 18. This oil is preferably led to discharge pipe 5 by pipe 21, but may be introduced to vessel 3, if desired.

15 Returning now to coke separators 8 and 9, when either is full, the flow of coke-carrying oil may be diverted to the other, the first being isolated, after which steam pressure may be applied from pipe 22, to drain oil from the coke and at 20 least partially dry it, the oil so removed being taken to tank 16 through pipe 23. After deoiling, the coke may be removed through discharge 24.

25 The coke so discharged, while oily, will be sufficiently dry for convenient handling and may be readily used as refinery fuel without further processing, if desired.

If desired, cooler 25 and water separator drum 26 may be installed in pipe 23. Also, pipe 23 may 30 be utilized as an auxiliary pipe for return of oil from circulation to tank, under manual control, if desired.

This system of operation has the advantage of 35 maintaining complete isolation of the coking chamber, regardless of the pressure conditions obtaining therein, and completely avoids all of those difficulties arising from attempting to operate mechanical devices, such as star wheels, for example, in the presence of highly abrasive coke. Further, since the oil used is refractory cracked stock, and is maintained relatively isolated from the heat of the coking chamber, it 40 does not lend a disturbing factor to the coking operation, and is little effected thereby.

The process is applicable not only to straight 45 spray coking systems, but also to those systems wherein a carrier, such as granular or fine fullers earth is admitted to the coking chamber to provide nuclei upon which coke may form. It is not 50 applicable to such processes as those which form as a residual product a coke suspended in a heavy oil.

I claim:

1. In a process of reducing heavy oils to relatively dry granular coke, the method which com-

prises, continuously subjecting the heavy oil to spray coking in a coking zone, maintaining a pool of refractory oil, isolated from atmosphere, beneath and in restricted communication with said coking zone, continuously collecting freshly formed coke granules in said pool, continuously withdrawing from said pool the mixture of oil and coke, and separating the oil and coke.

2. In a process of reducing heavy oils to relatively dry granular coke, the method which comprises, continuously subjecting the heavy oil to spray coking in a coking zone, maintaining a pool of refractory oil, isolated from atmosphere, beneath and in restricted communication with said coking zone, continuously collecting freshly formed coke granules in said pool, continuously withdrawing from said pool the mixture of oil and coke, separating the oil and coke, returning the former to said pool, and cooling the same intermediate withdrawal from the pool and return to it.

3. In apparatus for reducing heavy oils to relatively dry granular coke, a coking chamber, means for continuously spraying oil therein under high temperature conditions for evaporation and the formation of granular coke, means to remove vapors from said coking chamber, a container sealed to atmosphere and located beneath said coking chamber, means establishing restricted communication between the bottom of said coking chamber and the top of said container, and means for maintaining a pool of oil in said container, said last-named means in-

cluding an oil circulation system having therein an oil-coke separator whereby the oil may be continuously withdrawn from and returned to said container while the coke withdrawn from the chamber in admixture with the oil may be continuously removed.

4. In apparatus as claimed in claim 3, a heat exchanger in said circulation system for cooling the oil before its return to said container.

- 10 5. In apparatus for reducing heavy oils to relatively dry granular coke, a coking chamber, means for continuously spraying oil therein under high temperature conditions for evaporation and the formation of dry granular coke, means to remove vapors from said coking chamber, a container sealed to atmosphere and located beneath said coking chamber, means establishing restricted communication between the bottom of said coking chamber and the top of said container, a pair of oil-coke separators, means for selectively establishing communication between said container and one or the other of said separators, means for selectively establishing communication between the oil outlet of one or the other of said separators and said container, means for continuously circulating refractory oil from said container to one of said separators and after removal of coke therefrom back to said container again, and means associated with the circulating means for maintaining a pool of oil in said container at a predetermined level.

ERNEST UTTERBACK.
